STEAM GENERATOR

Martin Frisch, Cranford, N. J., assignor to Foster Wheeler Corporation, New York, N. Y., a corporation of New York

Application November 19, 1936, Serial No. 111,638

13 Claims. (Cl. 122—336)

This invention relates to steam generators and more particularly pertains to steam generators of the vertical straight tube type. The general object of the invention is to provide a steam generator of the vertical straight tube type which incorporates the most desirable features of modern practice with the various component parts thereof so arranged that the generator may be readily adapted to meet very small, very large and all intermediate steam output requirements without the necessity for individually designing and constructing a generator for each new requirement.

Somewhat more specifically, the invention provides a steam generator of vertical straight tube design which may be adapted to various steam output requirements by changing only one dimension of the unit, its height, with the component parts so arranged that variations in this one dimension will result in a proportional variation in the furnace volume and the heating surface without any change in the width or length, and with the arrangement such as to require only very low head room for small units and less than the usual head room for large units than is now required by units of conventional design and comparable capacity.

Further objects of the invention are:

To provide a vertical, straight tube type generator which requires less head room, than conventional steam generators, and less space by reason of the elimination of the necessity for side aisles between generator units and the necessity for tube withdrawal spaces around the unit.

To provide a steam generator of the type indicated which includes all essentials necessary for high availability, reliability, low maintenance and high efficiency but with the elimination, or the reduction to a minimum, of all costly details of design and construction such as outside water wall connections which are required by the usual conventional designs.

To provide a steam generator of the type indicated, having more radiant heat absorbing surface per cubic foot of furnace volume than in conventional units and in which maximum heat absorption in the boiler proper is obtained with a lower draft loss than is customary in conventional types of generator units.

To reduce the cost of field erection of vertical straight tube steam generators by designing the unit so that a larger proportion thereof may be assembled in the shop than is now customary.

To simplify the supporting framework of a

steam generator of the type mentioned, so that a minimum amount will be required.

To provide a steam generator of the type mentioned, which will be suitable for outdoor operation and such that no building or protecting structure will be required.

To provide a steam generator of the type designated, in which it is possible to increase the load range obtainable by arranging the furnace volume with respect to the unit so that low rating operation need not result in excessive cooling of the flame.

To provide a steam generator of the character indicated, in which superheat control may be readily effected.

To provide a vertical straight tube steam generator in which the convection superheater is so arranged with respect to the other heating surface that there will be no direct flame impingement on the superheater and the gases, particularly where the unit is fired with pulverized coal, will make an abrupt change in direction of flow before entering the superheater so that a large proportion of the ash carried thereby will be thrown out into the furnace before the gases enter the superheater.

To provide a steam generator of the character indicated having a furnace so arranged with respect to the boiler that every part of the furnace volume is effective, thus permitting when necessary, higher rates of heat liberation than is now customary in practice.

To provide a vertical straight tube steam generator which may be constructed without any brick work, if necessary, or if brick work is desirable, to have the amount thereof a minimum and of very simple design.

To provide a steam generator of the character mentioned, the overall cost of which is less than the cost of conventional units of equal surface and reliability.

In the preferred embodiment of the invention herein disclosed, these and other objects are attained by providing a steam generator having a vertical, straight tube boiler through which the gas flow is substantially parallel to the drums, disposed between and flanked by two water cooled furnaces of standard but minimum width required for the best performance with pulverized, liquid or gaseous fuel, thereby providing the boiler with at least two exposures to radiant heat. In the other form of the invention herein disclosed, the vertical straight tube boiler is provided with a single laterally disposed furnace. The furnaces in both forms are entirely water-

cooled or may be water-cooled except for the firing end and the opposite end, if desired. The furnaces are fired from the front of the boiler by burners disposed adjacent the top or bottom or both top and bottom of the front walls and the gases flow to the rear of each of the furnaces where they turn vertically through 180°, the separate upper and lower streams combine, mix and return to the front ends of the furnaces where they make a change in their horizontal direction of flow of 180° to enter the boiler tube bank. These turns separate from the gas a substantial proportion of fly ash and cause it to deposit in the furnaces. A superheater is disposed at the inlet end of the boiler and by virtue of this location, possesses the characteristics of both a radiant and a convection superheater. After passing through the superheater, the gases flow through the boiler in a direction parallel to the boiler drum and across all of the boiler tubes, which are arranged in staggered rows from front to rear, with the result that maximum heat absorption in the boiler proper is obtained with a lower draft loss than in conventional units. The gases leave the boiler at the central portion of the rear of the boiler and flow to additional heat recovery apparatus such as an economizer and/or an air heater and thence into an induced draft fan. The boiler tubes are staggered but are readily removable into the furnaces and the water wall and superheater tubes are also readily removable into the furnaces.

The nature, objects and advantages of the invention will be understood from the following description considered in connection with the accompanying drawings forming a part thereof and in which:

Fig. 1 is a transverse vertical sectional view of steam generating apparatus embodying the invention, taken substantially on line 1—1 of Fig. 3;

Fig. 2 is a horizontal sectional view taken on line 2—2 of Fig. 1;

Fig. 3 is a longitudinal vertical sectional view, taken on line 3—3 of Fig. 1;

Fig. 4 is a side elevational view with parts in section;

Fig. 5 is a horizontal, partial sectional view, on an enlarged scale, of the area designated A in Fig. 2;

Fig. 6 is a partial vertical sectional view, on an enlarged scale, of the boiler header arrangement;

Fig. 7 is a transverse vertical sectional view of another form of boiler embodying the invention; and

Fig. 8 is a horizontal sectional view, taken on line 8—8 of Fig. 7.

Like characters of reference indicate the same or similar parts in the several views.

Referring to Figs. 1 to 6 inclusive of the drawings, the steam generator illustrated has a rectangular casing or setting including a front wall 10, a rear wall 11 and side walls 12 and 13. The generator is provided with two spaced parallel furnaces 14 and 15 which are disposed adjacent the side walls 12 and 13 respectively of the setting. The generator is also provided with a steam generating section or boiler 16, which is disposed intermediate the spaced furnaces but is somewhat shorter in length. The furnaces and boiler are of rectangular configuration and are disposed in parallel relationship, as shown.

The boiler consists of straight vertically disposed tubes 17 arranged in rows extending transversely to the axis of the boiler with the tube rows

arranged in spaced pairs or groups of two rows each, with the tubes in the rows of each group arranged in staggered relationship, as clearly indicated in the drawings, particularly in Fig. 5. The lower ends of these tubes are rolled into a plurality of square headers 18 which are spaced somewhat from each other so that ash which separates from the combustion gases in the boiler may drop freely into the soot hopper 19 below. The upper ends of the boiler tubes 17 are rolled into square headers 20 which are arranged in two spaced rows extending longitudinally of the boiler. The headers 18 and 20 are arranged in staggered relationship, as shown more clearly in Fig. 6, that is to say, alternate headers are disposed at higher elevations than the other headers. Downcomers 21 connect the lower end of the boiler drum 22 with the central portions of the lower square headers 18. These downcomers extend through the central part of the boiler but are segregated from the boiler tubes and are protected from contact with the combustion gases by suitable refractory or other material 23. If desired, a passage between the downcomers may be provided for access. Headers 20 are connected to headers 24 through upcomers 25 and headers 24 are connected to the upper portion of drum 22 through a plurality of risers 26. The boiler tube bank also includes a plurality of rows, five rows in the form shown, of boiler tubes 27 which are larger than the tubes 17. Tubes 27 may conveniently be 3½ inches O. D., whereas tubes 17 may be 2 inches O. D. A superheater 28 consisting of a plurality of rows of 2 inch O. D. loop tubes as shown, is disposed at the inlet end of the boiler 35 16 ahead of the boiler tubes 27 with respect to the path of flow of the gases through the boiler. The side walls 29 and 30 of the boiler have a row of 3½ inch boiler tubes 31 disposed along the boiler side of these walls for their entire lengths. 40 These tubes 31 are connected into the headers 18 and 20. A plurality of rows of 3½ inch O. D. tubes 32 and 33 are disposed between the front ends of the side walls 29 and 30 of the boiler and the front wall 10 of the boiler setting to provide 45 slag screens for the gases entering the boiler from the furnaces 14 and 15. These tubes 32 and 33 may be disposed, as indicated in Fig. 2, or one or more rows of these tubes may be disposed in front of the superheater 28, if desired.

The boiler drum 22 is provided with a steam washer and drier 35 which is more fully disclosed and claimed in the copending application of Martin Frisch and Walter F. Keenan, Jr., Serial No. 110,310, filed November 11, 1936.

A plurality of steam risers 36 connect the upper end of boiler drum 22 with a steam drum 37 disposed above drum 22 and transversely with respect thereto. A steam line 38 connects steam drum 37 with the inlet header of superheater 28. 60

In the form of invention disclosed in Figs. 1 to 6 inclusive, the steam generating section or boiler 16 is suspended from supporting framework. This framework includes vertically disposed columns 39, one of which is placed at each corner of the boiler section 16, spaced longitudinally disposed girders 40 and 41 which are secured to the upper ends of the columns 39 and transverse girders 42 which extend between and are secured to the girders 40 and 41. The boiler drum is suspended by spaced cradles 43 which are supported by the spaced girders 42. The boiler circulating tubes and headers to which they are connected are suspended by a plurality of hanger rods 44 which are secured at their upper 75

ends to the girders 40 and 41. The steam drum 37 is supported in cradles 45 which rest upon the upper surface of girders 40 and 41. With this arrangement it will be seen that the steam generating or boiler section in its entirety, excepting the steam drum 37, is supported by being suspended from points or supporting members above the boiler section.

The furnaces 14 and 15 are entirely water cooled. However, for low capacity installations the firing wall and the rear wall may be installed without water cooling. The water wall tubes for each furnace are designated 46 and these tubes are suitably connected by headers which are connected into the circulating system. The furnaces are supported by columns 47, auxiliary columns 48 which are disposed at the outer side walls of the furnace, main girders 49 which are supported by the columns 47 and 39 and by a plurality of auxiliary girders or beams 50 which extend between the columns 48. As may be seen in Fig. 1, a plurality of hanger rods 51 which are connected at their upper ends to the girders 40 and 41 aid in supporting portions of the furnaces and the water walls thereof. The superheater tubes as may be seen in Fig. 3, are suspended by hanger rods 52 from a beam 53 extending between the main girders 40 and 41.

Each of the furnaces 14 and 15 is fired by a plurality of spaced fuel burners disposed in the front wall 10 of each furnace. The burners 55 are located adjacent the upper ends of the front walls 10 of the furnaces and burners 56 are disposed adjacent the lower ends of the front walls 10 of the furnaces as clearly shown in Figs. 1, 3 and 4 of the drawings. These burners are arranged to project streams of fuel and air through the spaces between the water wall tubes 46 and may be arranged similarly to the burners disclosed in the copending application of Martin Frisch, Serial No. 444,906, filed April 17, 1930. Fuel and primary air are supplied to the burners through conduits 57 to which the fuel is supplied from any suitable source such as a storage bin or pulverizing mill. Secondary air for the burners is supplied through an air conduit 58 which connects with an air casing 59 disposed outwardly of the front wall 10 of the boiler casing. Air from the casing 59 is supplied to air ducts 60 and 61 disposed respectively above and below the fuel nozzles of the burners 55 and 56. With the burner arrangement disclosed, the stream of products of combustion produced by each of the burners may be directed horizontally throughout the lengths of the furnaces or may be directed vertically upward or vertically downward depending upon the quantity and velocity of the air streams supplied through the air ducts 60 and 61. The fuel burners 55 and 56 direct separate spaced streams of products of combustion toward the rear walls 11 of the furnace, adjacent to which the upper stream turns downwardly and then forwardly through an angle of 180° and the lower stream turns upwardly and then forwardly through approximately the same angle. The two streams impinge upon and mix with each other at points near the rear walls 11 of the furnace and substantially midway between the top and bottom walls of the furnace, after which they flow toward the front of the furnace as indicated in Figs. 3 and 4. Upon reaching the front end of each of the furnaces, the returning streams of products of combustion turn horizontally through an angle of 180° and pass over the slag screens 32 and 33 and flow

into the chamber 62 disposed between the two furnaces and the front end of the boiler section 16 and impinge upon and mix with each other. These streams then make another horizontal turn through an angle of 90° and flow over the superheater tubes 28, boiler tubes 27 and thereafter flow over all of the boiler tubes 17 after which they enter a flue 63 disposed at the rear end of the boiler section 16. The gases flow downwardly in the flue 63 through the return bend section 64 and upwardly through the vertically disposed section 65 which delivers the gases to an induced draft fan 66 which in turn delivers them to a stack 67. In the form shown in Fig. 4, an air heater 68 is disposed in the flue section 65 and air is supplied to this air heater by a forced draft fan 69. If desired, an economizer may be disposed in the return bend section 64 preferably at its inlet portion 70.

The firing arrangement disclosed and the method of firing carried out thereby accomplishes several desirable results. Among these may be mentioned the fact that all of the furnace volume of each furnace is fully utilized. This will be apparent from an inspection of Figs. 3 and 4, particularly wherein the lines designating the flow of the streams of products of combustion indicate that the gases flow through substantially all portions of each of the furnaces. At the points or zones where the upper and lower streams of products of combustion impinge upon each other, intensive mixing occurs which accelerates combustion to a maximum and reduces stratification of the gases to a minimum. Inasmuch as the gases and burning fuel are forced to make two changes in direction of approximately 180° each prior to their entering the superheater and boiler, a larger proportion of suspended ash will be precipitated within the furnaces than in conventional units. 40

The method of firing disclosed herein is disclosed and claimed in a copending application of Martin Frisch, Serial No. 111,639, filed November 19, 1936. 41

The boiler may be fitted with a plurality of 43 suitable soot blowers disposed so as to face the superheater and with several soot blowers placed under the superheater and with a plurality of stationary pipe dust blowers 71 which are disposed so that their nozzles open up into the 50 main bank of boiler tubes in the clearances between the lower headers 18. Additional soot blowers may be provided to serve the economizer and lancing doors may be provided for cleaning the slag screens. 55

The straight boiler tubes 17 are removable into the furnaces 14 and 15 through the lanes, one of which is designated R in Fig. 5, provided by the spacing of the pairs or groups of boiler tubes. This spacing is great enough to permit 60 the removal of any boiler tube including the larger tubes 31. The tubes 27 are also arranged in rows which are spaced sufficiently to permit the removal of any of the tubes of this group through the furnaces 14 and 15. This ready 65 method of tube removal possesses at least two advantages over the usual method of removing tubes from straight tube boilers. These advantages are first, complete elimination of any danger of scoring the tube holes when attempting to remove bagged or blistered boiler tubes and second, no tube removal spaces in the front or rear of the boiler need be provided which means that a straight tube steam generator may be installed in spaces where the installation of 75

standard straight tube boilers would be entirely out of the question. Additionally with this arrangement, the boiler drum may be thinner than is required for bent tube types of boilers because of the higher ligament efficiency. For this reason and because the cost of the simple square headers used will be less than the cost of a mud drum, the cost of this type of boiler will be less for high pressures than for conventional types.

10. It will be perceived that each steam generating tube will have the full circulating head acting upon it. In this respect the boiler arrangement disclosed herein is superior to conventional straight tube boilers in which the circulating head progressively decreases from row to row toward the top of the boiler. As a result, circulation difficulties with the type of boiler herein disclosed should be non-existent.

15. In the forms of the invention shown, the gases from both furnaces flow over the superheater 28. However, if desired, the superheater may be so arranged that the gases from one furnace may pass over the entire superheater and the gases from the other furnace may by-pass or 20. pass only over a part of the superheater. This arrangement may be effected without the necessity of employing dampers or of by-passing any of the steam generating surface.

25. Figs. 7 and 8 illustrate more or less diagrammatically the invention embodied in a boiler having a single furnace disposed laterally of the steam generating section. In its essentials, this form of the invention is the same as the form shown in Figs. 1 to 6. The boiler section includes 30. a plurality of vertical straight tubes 80 connected to a plurality of square headers 81 arranged in the manner shown in Fig. 6, with a plurality of downcomers 82 disposed along side wall 83. A single drum 84 is disposed longitudinally of the 35. boiler section at its upper portion thereof. The furnace 85 is entirely water cooled as shown, and burners 86 and 87 are disposed in the front wall 88 of the furnace adjacent the upper and lower portions thereof as shown in Fig. 7. The streams 40. of products of combustion from these burners flow through the furnace and the boiler section as described in connection with Figs. 1 to 6. After 45. the gases have mixed and have returned to the front end of the furnace 85, they turn through an angle of 90° and pass over slag screen 89, after 50. which they make another turn of 90° and flow over the superheater 90, thence over the group of larger steam generating tubes 91, after which they flow over the smaller steam generating tubes 55. 80. The gases pass out of the boiler at the rear end of the steam generating section through a flue 92.

60. The downcomers 82 may be shielded from contact with the combustion gases. The boiler tubes 80 and 91 are grouped similarly to the tube arrangement shown in Figs. 1 to 6 and each of these tubes is readily withdrawn through the furnace 85 in the same manner as described in connection with the other form of invention herein disclosed.

65. With these arrangements of component parts of a steam generator, it will be perceived that a change in the vertical dimension only of the generator and the several component parts thereof will result in a proportional increase in furnace 70. volume and heating surface, in consequence of which steam generating units may be provided for any steam output requirements whether large or small, by merely varying the height of the unit without changing either the width or length thereof. In consequence, the same design may

be utilized for all steam output requirements, thereby eliminating the necessity for separately designing generators for every new use. By the use of a plurality of water cooled furnaces, it is possible to maintain the desirable ratio of water-cooled surface to the furnace volume or to the rate of fuel firing, as the size of the generator is increased. The arrangement is so compact that very small units require only very low head room and large units require proportionately greater 10 head room but less than is required in conventional designs for the same steam output capacity.

15. Since all of the tubes of the generator are removable into the furnaces, there is no need for side aisles between units to provide tube withdrawal spaces. Accordingly, a series of units constructed in accordance with the invention, may be installed side by side with a passage only at an end of the row of units or at some intermediate point which will permit access to the rear 20. of the row of units. However, such aisles as may be necessary to the rear may be much narrower than in conventional arrangements because no access to any part of the units through the sides thereof is necessary for any purpose.

25. The heat recovery devices, such as air heaters and economizers as well as the fans, may be disposed below the boiler and furnaces if desired, and may be located either on the operating floor or on a basement floor. Such an arrangement 30. entirely eliminates the necessity for overhead supporting structures for these devices.

35. Any essential auxiliary equipment may be located at the front of the units on the operating aisles and all parts of the boiler are accessible for 40. repairs from within the furnace. For removing the ash when pulverized coal firing is used, a simple and low cost ejector system may be installed with several openings connecting to the furnaces and with valves which are readily controllable from the front of the boiler. Such ash as may stick to the ash receiving hoppers at the bottom of the boiler and which cannot be blown away by the soot blowers can be similarly removed.

45. With the arrangement disclosed, it is apparent that the furnaces may be built in sections by sectionalizing the headers and that they may be shop assembled and shipped as units complete with insulation and casing.

50. Steam generating units embodying the invention are suitable for outdoor operation without any housing means therefor since all of the component parts are included within or below the casing of the unit.

55. Although the invention has been disclosed in connection with steam generating units having one and two furnaces respectively, which are disposed in parallel relationship with each other and with the boiler section, it will be understood that more than two furnaces may be utilized in a unit without transcending the principles of the invention. It will also be understood that various changes may be made in the location and arrangement of the several component parts of the 60. steam generating units without departing from the invention. Accordingly, it will be understood that no intention is entertained to limit the invention except by the scope of the claims appended.

70. What is claimed is:

75. 1. A steam generator comprising a setting, a steam generating section in the setting, an undivided furnace in the setting laterally disposed with respect to the steam generating section and

separated therefrom, a gas passage at one end of the furnace connecting the furnace and said section, and means at said one end of the furnace for producing a stream of products of combustion which flows through the furnace toward the other end thereof and then returns to said one end and thereafter flows through said gas passage and through the steam generating section.

5 2. A steam generator comprising a setting, a steam generating section in the setting, an undivided furnace in the setting laterally disposed with respect to the steam generating section and separated therefrom, a gas passage at one end of the furnace connecting the furnace and said section, and means at said one end of the furnace for producing a plurality of spaced streams of products of combustion which flow through the furnace toward the other end thereof and then return to said one end and thereafter flow 10 through said gas passage and through the steam generating section.

15 3. A steam generator comprising a setting having enclosing walls, a steam generating section in the setting, a furnace in the setting laterally disposed with respect to the steam generating section and separated therefrom by wall means, a gas passage at one end of the furnace connecting the furnace and said section, and burners at the upper and lower portions of said one end of the 20 furnace for producing spaced streams of products of combustion directed toward the other end of the furnace which flow through the furnace, through said gas passage and through the steam generating section.

25 4. A steam generator comprising a setting, a steam generating section in the setting, an undivided furnace in the setting at each side of the steam generating section and separated from the latter, a gas passage at one end of each furnace 30 through which gases flow into the same end of the steam generating section, and means at said one end of each furnace for producing a stream of products of combustion which flows through the furnace toward the other end thereof and then returns to said one end and thereafter flows 35 through the gas passage and the steam generating section.

40 5. A steam generator comprising a setting, a steam generating section in the setting, an undivided furnace in the setting at each side of the steam generating section and separated from the latter, a gas passage at one end of each furnace through which gases flow into the same end of the steam generating section, and means at said one end of each furnace for producing a plurality of spaced streams of products of combustion which flow through the furnace toward the other end thereof and then return to said one end and thereafter flow 45 through the gas passage and the steam generating section.

50 6. A steam generator comprising a setting having enclosing walls, a steam generating section in the setting, a furnace in the setting at each side of the steam generating section and separated from the latter by wall means, a gas passage at one end of each furnace through which gases flow into the same end of the steam generating section, and burners at the upper and lower portions of said one end of each furnace for producing spaced streams of products of combustion directed toward the other end of the furnace which flow through the furnace from end to end, thence through the gas passage and through the steam generating section.

55 7. A steam generator comprising a setting, a

steam generating section in the setting, an undivided furnace in the setting laterally disposed with respect to the steam generating section and separated therefrom, a gas passage at one end of the furnace connecting the furnace and said section, a superheater disposed in the path of flow of the gases between said gas passage and the steam generating section, and means at said one end of the furnace for producing a stream of products of combustion which flows through the furnace 10 toward the other end thereof and then returns to said one end and thereafter flows through said gas passage and through the steam generating section.

15 8. A steam generator comprising a setting, a steam generating section in the setting, an undivided furnace in the setting at each side of the steam generating section and separated from the latter, a gas passage at one end of each furnace through which gases flow into the same end of the steam generating section, a superheater disposed in the path of flow of the gases between said gas passages and the steam generating section, and means at said one end of each furnace for producing a stream of products of combustion 20 which flows through the furnace toward the other end thereof and then returns to said one end and thereafter flows through the gas passage and the steam generating section.

25 9. A steam generator comprising a setting, a steam generating section in the setting, an undivided furnace in the setting laterally disposed with respect to the steam generating section and separated therefrom, a gas passage at one end of the furnace connecting the furnace and said section, a plurality of tubes forming a slag screen in the path of the gases flowing from the furnace to said section, and means at said one end of the furnace for producing a stream of products of combustion 30 which flows through the furnace toward the other end thereof and then returns to said one end and thereafter flows through said gas passage and through the steam generating section.

35 10. A steam generator comprising a setting, a steam generating section in the setting, an undivided furnace in the setting at each side of the steam generating section and separated from the latter, a gas passage at one end of each furnace 40 through which gases flow into the same end of the steam generating section, a plurality of tubes forming a slag screen in the path of the gases flowing from each furnace to said section, and means at said one end of each furnace for producing a stream of products of combustion which flows through the furnace toward the other end thereof and then returns to said one end and thereafter flows through the gas passage and the steam generating section.

45 11. A steam generator comprising a setting, a steam generating section in the setting including a bank of steam generating tubes having their major portions at least extending substantially transversely of the longitudinal axis of said section, a furnace in the setting separated from said section and wherein gases are produced for flow through said section, the path of flow of the gases through said section being transverse to the steam generating tubes therein, downcomers within said bank of steam generating tubes, and means for shielding the downcomers from contact with the gases, said downcomers and shielding means being disposed to divide the gases flowing through said section into a plurality of paths.

50 12. A steam generator comprising a setting, a

steam generating section in the setting including a bank of steam generating tubes having their major portions at least extending substantially transversely of the longitudinal axis of said section, a furnace in the setting separated from and at substantially the same elevation as said section and wherein gases are produced for flow through said section, the path of flow of the gases through said section being transverse to the steam generating tubes therein, downcomers disposed intermediate the side walls of the steam generating section, and means for shielding the downcomers from contact with the gases flowing through said section.

10 15 13. A steam generator comprising a setting, a

steam generating section in the setting including a bank of steam generating tubes having their major portions at least extending substantially transversely of the longitudinal axis of said section, a furnace in the setting separated from and 5 at substantially the same elevation as said section and wherein gases are produced for flow through said section, the path of flow of the gases through said section being transverse to the steam generating tubes therein, downcomers disposed intermediate the side walls of the steam generating section, and means for completely shielding the downcomers from contact with the gases flowing through said section.

MARTIN FRISCH. 15
